UNITED STATES PATENT OFFICE.

ORIE E. VESSELS, OF INDIANAPOLIS, INDIANA.

PRINTER'S QUOIN.

No. 911,094.

Specification of Letters Patent.

Patented Feb. 2, 1909.

Application filed April 25, 1907. Serial No. 370,279.

To all whom it may concern:

Be it known that I, ORIE E. VESSELS, a citizen of the United States, residing at Indianapolis, in the county of Marion and State 5 of Indiana, have invented certain new and useful Improvements in Printers' Quoins, of which the following is a specification.

This invention relates to improvements in printer's quoins, and the object is, first, to 10 provide a positive means for locking together the two wedges of which the device is comprised so as to keep them from accidentally sliding and becoming loosened, and second, to provide means in the construction 15 of the quoin, to hold the type form on its feet and thereby take the spring out of the form.

I accomplish the objects of the invention by the mechanism illustrated in the accompanying drawing, in which—

20 Figure 1 is a detail in top plan view of a printer's chase and a piece of furniture, with my improved quoin in operative position. Fig. 2 is a vertical section on the line 2—2 of Fig. 1. Fig. 3 is a top plan view of my invention 25 in the same position as shown in Fig. 1, with parts broken away to illustrate the underlying formation, and Fig. 4 is a view of the inner oblique face of one of the wedges.

Like characters of reference indicate like 30 parts throughout the several views of the drawing.

5 is a portion of a printer's chase and 6 a piece of furniture such as is commonly used to bear against the type matter (not shown) 35 of the form and my improved quoin is shown between the furniture and chase. The latter comprises a pair of similar wedges 7 and 8 each having the lugs 9 at their thickened ends on their adjacent faces. These adjacent 40 faces are the oblique ones of the wedges and are provided with a longitudinal central flange 10 extending from the lug 9 to the opposite end of the wedge, and each of the lugs 9 is provided with a longitudinal slot 11 45 to receive the flange 10 of the opposite wedge. The inner oblique faces of each wedge on both sides of the flange 10 are provided with the teeth 13 to engage with the toothed end of a wrench, which is used in the usual way 50 for tightening up the form by sliding the wedge shaped sections of the quoin longitudinally upon each other.

As thus far described the construction is the same as quoins heretofore in use, and the 55 operation of such a device has not always

been satisfactory for the reason that the wedges will slide back and loosen under strain. I obviate the possibility of this loosening by forming a tooth or lug 16 at the inner end of the slot 11, and provide a series of 60 indentations or notches 18 along the major portion of the flange 10 the notches 18 forming the teeth 17. The tooth 16 of each wedge by entering a notch 18 in the flange of the opposite wedge provides a positive lock 65 which will prevent the accidental movement or slipping of the two wedges upon each other. The lugs 9 are long enough to hold the quoin members out of engagement at their portions 10, as shown in Figs. 1 and 3 70 and said lugs 9 are also longer than the teeth 16.

Another feature of my invention consists in adding an extension 20 to the outer face of each wedged section of the quoin at diagonally opposite appearing edges when the two wedges of the quoin are assembled. The quoin will be turned when placing it in the form so that the shoulder formed by the extension 20, on that face which is adjacent to 80 the furniture 6, will be lowermost. The thickened portion of the opposite wedge will be up, as clearly shown in Fig. 2. This thickening of the quoin at the parts named 85 has a tendency to tilt the quoin in a direction to force down the type form, so as to keep the latter on its feet and take the spring out of the type form.

Having thus fully described my invention what I claim as new and wish to secure by 90 Letters Patent of the United States, is—

1. A printer's quoin comprising a pair of wedges with oblique adjacent faces, the thick end of each wedge having a lug to bear against the other wedge, a longitudinal centrally located flange extending from each lug to the thin end of its wedge, said flange having a series of indents to form a series of teeth, there being a tooth on each side of each indentation, said lugs on the thick ends of the 100 wedges being grooved to receive the flange of the opposite wedge and said lugs each having an integral tooth no longer than its lug at the inner end of its groove to engage a corresponding one of the indents of the longitudinal flange to keep the wedges from sliding in either longitudinal direction on each other from the vibration of the press said lugs being long enough to hold the flanges out of contact with each other. 105 110

2. A printer's quoin comprising a pair of wedges with oblique adjacent faces, their opposite or outside faces having a projection or shoulder along one longitudinal edge at diagonally opposite corners of the quoin when in operative position.

In witness whereof, I, have hereunto set

my hand and seal at Indianapolis, Indiana, this, 13th day of April, A. D. one thousand nine hundred and seven.

ORIE E. VESSELS. [L. s.]
